United States Patent Office

Des. 198,169
Patented May 12, 1964

198,169

DOLL

Stephen M. Levy, 9 E. 37th St., New York 16, N.Y.

Filed Feb. 19, 1963, Ser. No. 73,636

Term of patent 3½ years

(Cl. D34—4)

FIG. 1 is a front perspective view of a doll, showing my new design;

FIG. 2 is a rear perspective view thereof; and

FIG. 3 is a fragmentary side elevational view thereof.

I claim:

The ornamental design for a doll, substantially as shown.
